UNITED STATES PATENT OFFICE.

ERNEST N. CHASE, OF AUBURN, MAINE.

CLAMPING DEVICE FOR ATTACHING HEELS TO SHOES.

1,405,098.

Specification of Letters Patent. Patented Jan. 31, 1922.

Application filed February 5, 1921. Serial No. 442,726.

To all whom it may concern:

Be it known that I, ERNEST N. CHASE, a citizen of the United States, and a resident of Auburn, county of Androscoggin, and 5 State of Maine, have invented certain new and useful Improvements in Clamping Devices for Attaching Heels to Shoes, of which the following is a full and complete specification.

10 In gluing high heels to women's shoes, it is a general practice to hold the wooden heel against the base of the shoe for a continued length of time to allow the glue to set. Where this operation follows one in which 15 a last is used in the shoe, and where the last is allowed to remain during the heel attaching operation it follows that the last is rendered useless for its primary purpose in the assembly of the shoes. Again, where 20 large numbers of shoes have the heels applied simultaneously there is a consequent loss of time in the use of the lasts in the specific operations in which a last is necessary.

It has been found that by removing the 25 last from the shoe and substituting a special form of clamp to hold the heel during the gluing operation, improved results and advantages are obtained. At the same time the last is returned to further use in the 30 assembly of the shoe proper.

My invention consists in the provision of a heel attaching clamp which is used in place of the last and serves to materially aid in the proper gluing of the heel to the 35 shoe in an improved and advantageous manner.

One form of my invention is described in the following specification and illustrated in the drawing, in which—

40 Fig. 1 is a view of the clamp in operation;

Fig. 2 is a side elevation of the clamp, showing certain parts in longitudinal section,

45 Fig. 3 is a detailed view of the strap carrying means, and

Fig. 4 is another form of strap adjustment.

I have shown a clamping base 4 fitting the heel of a woman's shoe 5 indicated in Fig. 50 1 by dotted lines. This clamping base is drilled as at 6 to receive the upper end of a bench spindle 7 upon which it may be supported. The base extends from its rear-most tapered end 8 forward to the arch of the shoe 55 as indicated at 9.

Centrally of the clamp base and at an angle of 45 degrees with its top and bottom surfaces there is provided a hole 10 carrying a stem 11. This stem 11 is generally rectangular in cross section. The upper face of the 60 stem opposite the clamping base 4 is slotted as at 12. A pivot member 13 passes laterally through the stem and the slot 12. A bar 14 is carried upon the pivot member 13 and is free to move in a vertical plane. The 65 upper end of the stem 11 is drilled longitudinally for the greater portion of its length to provide a sleeve 15 which forms a smooth bearing for a rod 16 slidably therein. The stem is slotted vertically as indicated in Fig. 2 at 17 and 18. This slot 70 extends over a considerable distance for a purpose to be hereinafter set forth.

The bar 16 which slides in the sleeve 15 carries near its lower end a lug 19 which 75 is attached by means of a pin 20 running through the stem 16. The outer end of the lug 19 is transversely drilled. At its upper end the stem 16 carries a cross arm 21 80 to the extremities of which are pivoted sheet metal or other analogous links 22 by means of over-lapping ears 23 and pins 24, which latter are riveted to the ears and pass through the cross member 21.

An L-shaped hand lever 24 is provided consisting of a handle 25 and bifurcated ends 26 laterally disposed with respect to the axis of the handle 25. This lever is pivoted to the lug 19 by a pin 27 passing through the bifurcated members and the lug. The free 90 ends of the bifurcated members are drilled transversely to carry a rivet upon which one end of the bar 14 is pivoted. The bar 14 and the bifurcated members 26 are adapted to form a toggle when the bar approaches a 95 position parallel to the stem 11.

The members 22 have long narrow slots 28 in which are looped the ends of a flexible strap 29 made of canvas or similar material. One end of the strap 29 is firmly attached 100 as at 30. The opposite end 31 of the strap is held in adjustable position with respect to the running part of the strap by means of a fastening consisting of two plates 32 and 33. The plate 32 has an inturned lip 34. Both 105 plates are drilled to permit the passage of locking screws 35 which are fastened by means of nuts 36.

It will be evident that this device is used after the plate 4 has been mounted upon the 110

bench spindle 7. A shoe which is complete except for the heel and from which the last has been removed is then fitted upon the clamp plate 4 as indicated in Fig. 1. The 5 wooden heel with the requisite glue is placed in final position upon the upturned shoe. It will be apparent that during the above operation the strap 29 will have taken a position loosely around the shoe due to the fact 10 that the handle 25 is parallel to the stem 11 and that the rod 16 is therefore retracted.

The canvas strap will have been previously adjusted by means of the free end 31 being held in the locking plates 32 and 33, 15 to give the requisite pressure desired. With the handle 25 in the retracted position the strap 29 is lifted over the broad base of the heel and allowed to conform to the latter. By pulling outward upon the handle 25 the 20 leverage of the arms 26 and bar 14 forms a toggle. The strap is thus tightened and forms a binding between the heel and the shoe. The shoe together with the clamp and the heel is then lifted from the spindle 25 7 and set aside until such time as the heel has become firmly attached in place. The 30 clamp is then readily removed and the operation repeated upon another shoe.

An alternative form of strap adjustment 35 is shown in Fig. 4 in which the strap 29 is indicated as formed in two parts connected by a buckle 37 having a transverse rib 38. An upstanding lip 39 projects from rib 38. The free end of strap 29 is passed through 40 one opening of the buckle and back through the other opening. The tension of the toggle on the strap will be sufficient to maintain a firm grip between the contacting parts.

A series of holes 40 has been provided in 45 the face of the plate 4 to receive nails during use of the implement in repairing shoes.

It is to be noted that the action of the clamp is such as to draw the heel firmly against the rear edge of the outer sole and 45 insure a close and neat joint therewith. In this manner the finished appearance of the completed shoe is rendered uniformly excel-

lent and is entirely independent of the degree of care of the operator.

By the use of this clamp it is possible to 50 keep the lasts in active and constant use without the former inconvenience of utilizing them as supporting means during the heel attaching operation.

Other advantages will be evident from 55 the above description and various changes can, of course, be made in material and construction without departing from the spirit of my invention, as defined in the following claims.

What I claim is:

1. In combination, a clamp base, a recessed stem thereon, a strap carrying member slidable in the recess of the stem and toggle means connecting the stem and the 60 strap carrying member.

2. In combination, a clamp base, a recessed stem thereon, a strap carrying member slidable in the recess of the stem, a bar pivoted to the stem, and a lever pivoted to 70 the strap carrying member and connecting with the bar.

3. In combination, a clamp base, a recessed stem thereon, a strap carrying member slidable in the recess of the stem, a bar 75 pivoted in the stem, and a lever pivoted to the strap carrying member, said lever having one of its arms connected to said bar.

4. In combination, a clamp base, a recessed stem thereon, a strap carrying member having cross arms, a link connected to each cross arm and a flexible strap connecting said links, said strap carrying member slidable in the recess of the stem, and toggle means connecting the stem and the member. 80

5. In combination, a clamp base, a recessed stem thereon, a member slidable in the recess of the stem, toggle means connecting the stem and the member, and an adjustable strap carried by said member. 85

In testimony whereof, I have hereunto affixed my signature.

ERNEST N. CHASE.
